CLAIM

The ornamental design for a caddy for positive airway pressure breathing device, as shown and described.

DESCRIPTION

FIG. 1 is a front perspective view of a caddy for positive airway pressure breathing device showing our new design in a sample environmental setting;

FIG. 2 is an enlarged perspective view thereof, showing the caddy in isolation;

FIG. 3 is a reverse perspective view thereof;

FIG. 4 is another perspective view thereof, without the cradle and positive airway pressure breathing device;

FIG. 5 is a right side view thereof;

FIG. 6 is a left side view thereof;

FIG. 7 is a top view thereof;

FIG. 8 is a bottom view thereof;

FIG. 9 is a rear view thereof; and,

FIG. 10 is a front view thereof.

One or more views (e.g., bottom view) may not be shown as those views are unornamented or simply not claimed in a given embodiment.

The broken line showing of parts of the drawings is included for the purpose of illustrating use and environment and forms no part of the claimed design.
